Application February 27, 1946, Serial No. 650,666

15 Claims. (Cl. 250—36)

1

This invention relates to systems for selectively producing any one of a large series of frequencies such for example as are required for the carrier frequencies of radio transmitting and receiving systems.

Heretofore, there have been proposed three general types of systems for generating multiple carrier frequencies.

1. Harmonic generators such as high distortion vacuum-tube amplifiers.
2. Multi vibrators.
3. Crystal-controlled master oscillators plus frequency multipliers.

The first two types of systems have the very great disadvantage of lack of inherent frequency stability and their fundamental or base frequency tends to depart from desired fixed value. In other words, the resultant harmonics are greatly dependent upon temperature, humidity and similar ambient conditions affecting not only the generator tubes but also the components which determine the fundamental or base frequency. The third general type, has the advantage of stable fundamental frequency. In all the prior known arrangements, it has been extremely difficult without the use of extremely complicated and expensive duplicate equipment, to produce selectively any one of a large series, for example several thousand, of highly stabilized frequencies closely spaced in the frequency spectrum.

Accordingly, it is one of the principal objects of this invention to provide an improved system for selectively obtaining any one of a large series of frequencies closely spaced in the frequency spectrum, and with the same degree of frequency stability as is obtained with a stabilized generator such as a crystal-controlled oscillator.

Another object is to provide a system of producing any one of a series of frequencies over a very wide range of frequencies, and with substantially the same degree of stability in each selected frequency as that of a crystal-controlled oscillator.

Another object relates to a system for producing any one of a great number of carrier frequencies by using a master oscillator of the crystal-controlled type, and deriving under control thereof the desired frequency by multiplication and frequency conversion processes without correspondingly multiplying errors which tend to develop in the frequency conversion stages.

A feature of the invention relates to a system for producing any one of a very large series of radio carriers by separating the output of the master oscillator into a plurality of frequency

2

selector channels, and into a multiplier channel, and combining the outputs of all the channels so as to selectively obtain the desired frequency with exactly the same degree of stability as that of the master oscillator.

Another feature relates to an improved instrument which will select and emit any one of several thousand equally spaced frequencies within a high frequency range, for example of 20 to 40 megacycles. In accordance with this feature, each desired frequency is derived under control of a crystal-controlled master oscillator input operating for example at 100 kilocycles by combining exact multiples and sub-multiples 15 of the master oscillator frequency through the intermediary of adjustable local conversion oscillators, in such a way that any undesirable error in the local oscillator or local oscillators are automatically cancelled out. The desired frequency 20 is selected from, rather than controlled by the multiples and sub-multiples of the master frequency, and are, therefore, independent of the small variations in values of the circuit components such as are normally encountered in the 25 electronic circuits. As a result, the accuracy in percent of stability of the selected output frequencies is exactly that of the master oscillator.

A further feature relates to an improved instrument for selectively producing under control 30 of a master oscillator, such as a piezo crystal-controlled oscillator, any one of a large series, e. g., several thousand, of radio carriers which are very closely spaced in the frequency spectrum, and by employing only two calibrated dials. 35 These dials need not be calibrated to hair-line accuracy since the accuracy of the selected output frequency is determined primarily by the accuracy of the master oscillator.

A still further feature relates to a system for 40 deriving any one of a series of high frequency carriers under control of a master oscillator by subjecting waves derived under control of the master oscillator and in separate frequency selector channels to alternate addition and subtraction in respective frequency conversion stages in each channel so as to eliminate ambient errors in the local conversion oscillators in each conversion channel; and by subjecting waves derived from the master oscillator to a frequency multiplying action. The waves derived from the respective selector channels and from said multiplier channel are combined so as to produce any desired frequency among several thousand with the same order of stability as that of the master oscillator. This result is achieved through the 50 55

intermediary of only two calibrated dials, one associated with each of said selector channels so that one dial acts to select successive frequencies in accurately widely spaced increments, and the other dial associated with the other frequency selector channel acts to select subdivision increments within the said widely spaced increments.

A still further feature relates to the novel organization, arrangement and relative interconnection of parts which cooperate to produce an improved and highly stable multi-frequency generating and selecting system.

Other features and advantages not specifically enumerated will be apparent after a consideration of the following detailed descriptions and the appended claims.

Referring to the drawing, there is shown a master oscillator 10, which is preferably of the grid-controlled vacuum-tube type 11, whose frequency is stabilized by the piezo crystal 12 in the well-known manner. Merely for explanatory purposes, it will be assumed that oscillator 10 generates at a fixed frequency of 100 kilocycles. This oscillator controls three separate channels identified respectively as "Selector channel A"; "Selector channel B"; and "Multiple generator channel." The selector channel A is controlled by a frequency divider 13 of any well-known kind, whereby there is produced a sustained frequency wave which is one-half the frequency of oscillator 10, namely, 50 kilocycles. Likewise, the selector channel B is controlled by a frequency divider 14, which receives the 50 kilocycle waves from divider 13, and further subdivides them into sustained frequency waves which are one-fifth the frequency of the waves from divider 13, and therefore one-tenth the frequency of the waves from oscillator 10, namely, 10 kilocycles. For a description of typical frequency divider arrangements that may be used for the devices 13 and 14, reference may be had to "Electronic Engineering Handbook," by Batcher and Moutic, page 311. The master oscillator 10 also controls the multiple generator channel where it is subjected to a first frequency multiplier 15, which may have a multiplying factor of 10 to produce an output at 1 megacycle. This output is passed through the 1 megacycle filter 16, and thence to a second multiplier stage 17, which may have a multiplying factor of 5 to produce a 5 megacycle output. These latter waves are then passed through a 5 megacycle filter 18, whose output is further multiplied in frequency by frequency multiplier 19, which has a multiplying factor of 10 to produce at terminal 20 a 50 megacycle signal. For a detailed description of suitable frequency multipliers that may be used for the devices 15, 17 and 19, reference may be had to "Radio Engineering," by F. E. Terman, pages 338-341.

The 50 kilocycle waves from device 13 are applied to any harmonic producing device such as an overdriven grid-controlled vacuum tube 21, which produces in its output a spectrum of harmonics of the input frequency as described for example in Radio Engineering, by F. E. Terman, 1st edition, pages 221-225, published by McGraw-Hill Book Company, Inc., New York, N. Y. If desired, the device 21 may be any well-known form of wave distorting device which is rich in harmonics of a fundamental input frequency, such for example as any well-known form of "multi-vibrator" circuit such as described in pages 275-276 of book by F. E. Terman. Associated with the output of device 21 is an adjustable band-pass

filter 22, which is designed to pass a frequency band of 6.7 to 8.7 megacycles. Filter 22 is of a type which is capable of selectively passing with substantially uniform gain any desired narrow band-width of frequencies in its acceptance band of 6.7 to 8.7 megacycles. It may take any well-known form; such for example as a permeability tuned inductance with an adjustable permeability magnetic core. The pass-band at any given setting of filter 22 should preferably not exceed 700 kilocycles on either side of the desired frequency setting. The waves passed by filter 22 are applied to any well-known form of frequency mixer 23, which for example may be any of the known types of frequency converter tubes used in superheterodyne radio receivers and the like. Associated with filter 22 and mixer 23, is an adjustable frequency oscillator 24, which is of the "free running" type as distinguished from a stabilized oscillator such as a crystal-controlled oscillator. Oscillator 24 is designed to be adjustable so as to generate any fundamental frequency in the band 3 to 4 megacycles, and its output circuit is such that it selectively passes with maximum gain the second harmonic of the generated fundamental frequency, namely, any frequency between 6 to 8 megacycles. This second harmonic is impressed upon the mixer 23, where it beats with the 6.7 to 8.7 megacycle signal from filter 22. The tuning elements 25 and 26 of filter 22 and oscillator 24, are respectively ganged together so as to produce for all settings in conjunction with the usual intermediate frequency coupling circuits, a constant intermediate carrier frequency e. g., of 700 kilocycles which is amplified in the intermediate frequency amplifier 27. In other words, the output of amplifier 27 consists only of the intermediate frequency carrier representing the "difference" frequency between the frequency settings of elements 22 and 24.

The intermediate frequency carrier waves from amplifier 27 are then impressed on a mixer device 28 similar to device 21. At the same time, the second harmonic from oscillator 24 is passed through a 6 to 8 megacycle band-pass filter 29, the tuning element 30 of which is ganged for unitary operation to the aforementioned tuning elements 25, 26. The 6 to 8 megacycle waves from filter 29 are then impressed on the mixer 28 and the "sum" frequency between the intermediate frequency carrier waves from amplifier 27 and the 6 to 8 megacycle waves from filter 29 are selected by the adjustable filter 31, which is similar to filter 22, and has an acceptance band 6.7 to 8.7 megacycles. The tuning element 32 of filter 31 is ganged to the tuning elements 25, 26 and 30 for unitary operation therewith. As a result of this alternate subtraction and addition in the mixers 23 and 28, by the means described, the stability of any selected frequency in the band 6.7 to 8.7 megacycles in the output of filter 31, is determined primarily by the stability of the master oscillator 10, and is entirely independent of ambient changes in the frequency of oscillator 24, such for example as those resulting from humidity variations, temperature variations and the like. By this method, it is possible to select any frequency in the range 6.7 to 8.7 megacycles with as great a percent of stability as that of oscillator 10. The output of filter 31 is then multiplied in a frequency multiplier 33, which has a multiplying factor of 10 to produce any selected frequency in the range 67 to 87 megacycles. The selected frequency is then passed through an

adjustable band-pass filter 34 covering the 67 to 87 megacycle band, the tuning element 35 of which is ganged to the aforementioned tuning elements 25 and 26, 30 and 31.

The adjusting knob 36 which controls the ganged tuning elements is provided with a calibrated scale, which may have, for example, 40 main subdivision markings each representing a .5 megacycle step and covering the range from 67 to 86.5 megacycles. By this arrangement, one of 40 groups of frequencies each of .5 megacycle width in the 67 to 86.5 megacycle band can be selectively chosen by setting the knob 36 to the particular one of its 40 separate settings.

The selector channel B is substantially the same as channel A as far as filter 31, except that channel B is arranged to select in 50 successive steps of 10 kilocycle spacing or width, in the range 3.0 to 3.5 megacycles, by means of the unitary adjusting knob or dial 37.

With the examples of frequency given for channel A, the 10 kilocycle waves from subdivider 14, are passed through the distorter 38 similar to device 21, and the adjustable band-pass filter 39 which corresponds to filter 22 passes only frequencies in the band 3.0 to 3.5 megacycles. The local adjustable oscillator 40 similar to oscillator 24, is arranged to generate any fundamental frequency in the band 1.35 to 1.6 megacycles, and the second harmonic thereof is impressed upon mixer 41, which corresponds to mixer 23. The waves from devices 39 and 40, after passing through the mixer 31, are converted into beat frequencies and the lower or difference frequency of 300 kilocycles is selectively amplified in the intermediate frequency amplifier 42 corresponding to amplifier 27. The second harmonic from the oscillator 40 is also passed through the adjustable filter 43 corresponding to filter 29, and the output of amplifier 42 and the output of filter 43 are impressed upon the mixer device 44 corresponding to device 28. By means of the adjustable band-pass filter 45, the "sum" frequency in the output of mixer 44 is selected by the filter 45. The tuning elements 46, 47, 48 and 49 are ganged together for unitary operation by the single knob 37, which cooperates with a calibrated scale which may be marked in 50 subdivisions representing 10 kilocycle steps.

Assuming that the desired frequency is to be used as a transmitting carrier frequency, the switches 50 and 51 are in the positions shown in the drawing. As a result, the 50 megacycle waves from the multiple generator channel are applied through switch 50 to the 50 megacycle filter 52, the output of which is applied to the mixer device 53, which may be similar to devices such as 23. Also impressed upon the mixer 53 is the selected frequency in the 3.0 to 3.49 range at the output of filter 45. The mixer 53 is connected to a band-pass filter 54 which covers the range 46.5 to 47 megacycles representing the "difference" frequency between the output of filter 52 and the output of filter 45. The selected frequency in the output of filter 54 is then applied to another mixer device 55, similar to devices such as 23, upon which the output of filter 34 is also impressed. By means of a suitable filter 56, the difference frequencies between the outputs of filters 34 and 54, are selected and passed to the terminal 57, whence they may be connected to any well-known form of radio transmitter to act as the carrier or for any other purpose desired. The net result is that at the terminal 57, there can be produced in successive 10 kilocycle steps

any one of 2000 desired frequencies in the range from 20 to 40 megacycles, and each of these frequencies has exactly the same frequency stability as oscillator 10. In operating the device, the knob 36 is first set to an appropriate position representing the group in which the desired output frequency is located. The knob 37 can then be adjusted to a point representing the particular frequency in the selected group. If the terminal 57 is to be used for radio reception purposes, the switches 50 and 51 are operated so as to replace the 50 megacycle filter 52 by a 55 megacycle filter 58, and also to replace the 46.5-47 megacycle filter 54 by a 51.5-52 megacycle filter 59. The mixer 53 is also replaced by a similar mixer 60. The elements 58, 59 and 60 function exactly the same as the corresponding elements 52, 53 and 54, used for transmission, except that in this particular case the 2000 frequencies which result at the terminal 57 are in the band 15 to 35 megacycles which is a separate band from that above described for transmission, namely, 20 to 40 megacycles. While in the foregoing description, reference has been made to particular frequencies and ranges of frequencies, it will be understood that these are given merely for illustrative purposes, and for simplicity in explanation.

While certain specific embodiments have been disclosed herein, various changes and modifications may be made therein without departing from the spirit and scope of the invention.

What is claimed is:

1. A selective multi-frequency producing system comprising a master oscillator, a plurality of frequency selector channels, a frequency multiplier channel, each of said selector channels being supplied with any selectable control frequency in a series of control frequencies derived from said master oscillator; each selector channel including a local source of adjustable frequency oscillations, means to combine the said series of control frequencies with a selectable frequency from the local oscillator to produce a series of beat frequencies, means to select a particular beat frequency, and means to combine with said particular beat frequency the frequency from the local oscillator to produce a resultant beat equal to the selected control frequency, and means to correlate the control frequencies applied to each channel so that there appears in the output of one channel any one of a series of frequencies spaced apart "a" cycles per second in a predetermined range, and at the output of the other channel there appears any one of a series of frequencies spaced apart "b" cycles per second where "a" and "b" are related by an integer.

2. A frequency producing system according to claim 1 in which a separate frequency multiplier channel is controlled by said master oscillator, and means are provided for combining the output frequency of one of said selector channels with the output frequency of said multiplier channel to produce a desired frequency spacing between the output of the first channel and the frequency of said combined output.

3. A selective multi-frequency producing system, comprising a crystal-controlled master oscillator, a first frequency selector channel, a second frequency selector channel, means to derive from said master oscillator a first series of control frequencies, means to derive from said master oscillator a second series of control frequencies both series being electrically locked to the frequency of said master oscillator, filter

means for the first channel having an acceptance band width commensurate with the width of the said first series and adjustable to select therefrom a predetermined frequency F_a ; other filter means having an acceptance band commensurate with the width of said second series and adjustable to select therefrom a predetermined frequency F_b ; a frequency conversion system in said first channel including a local conversion oscillator which can be set to produce any frequency in a band of the same width as the acceptance band of the first-mentioned filter means but having a frequency difference F_d with said frequency F_a , means to mix a frequency from the local oscillator with said frequency F_a , means to select from the resultant mixture the frequency F_d ; other means to mix with said selected resultant F_d a frequency which is the same as the said frequency from said local oscillator to obtain a frequency F_a whose frequency stability is substantially independent of ambient changes in said local oscillator; a frequency conversion system in said second channel including a local conversion oscillator which is settable to produce any frequency in a band of the same width as the acceptance band of the second-mentioned filter means but having a frequency difference F_d with said frequency F_b , means to mix the frequency from the local oscillator of the second channel with said frequency F_b , means to select from the resultant mixture the frequency F_d ; other means to mix with said selected resultant a frequency which is the same as the said frequency from the local oscillator of the second channel to obtain a frequency F_b whose frequency stability is substantially independent of ambient changes in said local oscillator of the second channel; and means to combine the outputs of the two channels so that the setting of one channel produces frequencies within a desired range with "group" spacings between successive frequency settings and the setting of the other channel produces frequencies which are integral subdivisions of the set group frequencies of the first channel.

4. A selective multi-frequency producing system according to claim 3 in which the said filter means of each channel is ganged to the frequency adjusting element of the local oscillator of the same channel to maintain said frequency F_a constant for all settings.

5. A selective multi-frequency producing system according to claim 3 in which the output of the frequency converter system in each channel has an adjustable filter similar to the said filter means of the corresponding channel and having its adjusting element ganged thereto.

6. A multi-frequency selective system comprising a master oscillator, means including a first distorfer for deriving under control of said master oscillator a first series of frequencies, means including a second distorfer for deriving under control of said master oscillator a second series of frequencies, an adjustable filter for selecting from the first series a restricted band including a frequency F_a , a plural-stage frequency converter system upon which said first series is impressed, said converter producing at its output the same frequency as impressed on its input by alternate additions and subtractions from a local conversion oscillator; another adjustable filter for selecting from the second series a restricted band including a frequency F_b , a plural-stage frequency conversion system upon which the second series is impressed, said conversion system producing at its output the same frequency as is impressed

on its input by alternate additions and subtractions from a local conversion oscillator; a frequency multiplier channel connected to said master oscillator; means to mix the output of the second-mentioned frequency conversion system with the output of said frequency multiplier, means to select from said mixture a resultant band of frequencies; and means to mix the output of the first-mentioned frequency conversion system with the said resultant band to produce a series of frequencies each of which has substantially the same frequency stability as that of said master oscillator.

7. In a frequency-selecting system, a crystal-controlled master oscillator, a pair of frequency selector channels, a frequency divider and harmonic generator connected between said oscillator and each of said channels; an adjustable input filter connected to the output of the harmonic generator of the first channel; an adjustable frequency conversion oscillator for the first channel; a mixer device connected to said filter and oscillator to produce an intermediate frequency, another mixer device in said first channel upon which the said intermediate frequency is impressed and also a conversion frequency from said oscillator, a second adjustable filter connected to the output of said second mixer, said first and second mixers producing equal but opposite changes in the conversion frequency from said oscillator whereby the output frequency from the second mixer is the same as the frequency selected by the first-mentioned filter, the acceptance bands of both said filters being substantially alike, and the adjusting elements of said filters and said local oscillator being ganged together to produce in the first channel output group frequencies; an adjustable input filter connected to the output of the harmonic generator of the second channel, an adjustable frequency conversion oscillator for the second channel; a first mixer device connected to said filter and oscillator to produce an intermediate frequency, a second mixer device upon which the last-mentioned intermediate frequency is impressed and also a conversion frequency from the last-mentioned conversion oscillator, another adjustable filter connected to the output of the said mixer of said second channel, said mixer devices of the second channel producing equal but opposite changes in the conversion frequency from the associated conversion oscillator whereby the output frequency from the second mixer of the second channel is the same as the frequency selected by the said input filter of the second channel, the acceptance bands of both said filters of the second channel being substantially alike, and the adjusting elements of said filters and said local oscillator of the second channel being ganged together to produce at the output of the second channel equally spaced frequency increments representing integral subdivisions of the group output frequencies of the first channel.

8. A frequency-producing and selecting system comprising a crystal-controlled master oscillator, means to derive from said oscillator and in separate channels two different series of frequencies locked to the master oscillator frequency, frequency conversion means in the first channel including an adjustable input filter having an acceptance band commensurate with the first of said series, a local conversion oscillator, a plurality of successive mixer stages connected to said input filter and said conversion oscillator to produce at the output of the last mixer stage a

frequency which is the same as the input frequency selected by said input filter by alternate additions and subtractions with respect to the conversion oscillator frequency, an output adjustable filter having substantially the same acceptance band as said input filter, means for ganging the adjustable elements of the said filters and the said oscillator; frequency-conversion means in the said second channel having an adjustable input filter with an acceptance band commensurate with the said second series, said conversion means including a plurality of successive conversion stages with a common local conversion oscillator, whereby the output of the last stage has the same frequency as the selected input frequency from said input filter by alternate additions and subtractions with respect to the associated conversion oscillator frequency, an adjustable output filter connected to the last mixer and having substantially the same acceptance band as the input filter of the second channel, means for ganging the adjustable elements of both filters and of the associated local oscillator together; and a common combining network upon which the output of the first channel and the output of the second channel are impressed whereby the first channel can be set to produce a series of frequencies with uniform group spacings and the second channel can be set to produce a series of frequencies representing integral subdivisions of each of said groups of frequencies.

9. A system according to claim 8 in which the said means for deriving said two series of frequencies comprises two frequency dividers which are controlled by said master oscillator, the first frequency divider having connected between it and the said input filter a first channel a harmonic generator, and the second frequency divider having connected between it and the adjustable input filter of the second channel another harmonic generator, said frequency subdividers being connected in series with respect to the master oscillator.

10. An instrument for producing any desired highly stabilized frequency within a relatively wide range of frequencies comprising a crystal-controlled master oscillator, a first frequency conversion channel connected to said master oscillator through a frequency subdivider and harmonic generator, a second frequency conversion channel connected to said master oscillator through a second frequency subdivider in series with said first subdivider; each of said frequency conversion channels comprising a pair of mixer devices, means to apply to the mixer devices of a given channel the same local conversion oscillation frequency, means to apply to the first mixer device of each pair a respective selected frequency from the output of the corresponding harmonic generator, and means to select from the output of the second mixer of each pair a respective frequency which is the same as the said respective selected frequency by alternate additions and subtractions in said mixers with respect to their local conversion oscillator frequency; a single adjusting means for selecting the output frequencies of the first frequency conversion system in relatively widely spaced frequency spacings, another single adjusting means for selecting the output frequencies of the second frequency conversion system in relatively narrowly spaced frequencies representing integral subdivisions of said widely spaced frequencies, and a common combining network for the outputs of both said frequency conversion systems for selecting any

particular frequency which frequency has substantially the same stability as that of said master oscillator.

11. A system according to claim 10 in which said master oscillator is connected to a frequency multiplier channel, the output of which is mixed with the output of the said second frequency conversion system and said common combining network includes a mixer device upon which the output of the first-mentioned frequency conversion system is impressed and upon which the mixed output of the second frequency conversion system and said frequency multiplier channel is impressed.

15. 12. A frequency-selecting system comprising a pair of channels each including in sequence a frequency subdivider, a harmonic generator, an adjustable input filter, a first mixer, an intermediate frequency amplifier, a second mixer, and an adjustable output filter; a local frequency conversion oscillator for each channel and connected to the first mixer and also connected to the second mixer of the respective channel through a third adjustable filter, the adjusting 20 elements of all said filters for each channel and for the adjusting elements of channel oscillator being ganged together; a common crystal-controlled master oscillator connected to said frequency subdividers, a frequency multiplier channel connected to said master oscillator, a mixing network upon which the output of said multiplier channel is impressed and upon which the output of the second of said pair of channels is impressed, and another mixer device upon which the output of the first of said pair of channels is impressed and upon which the mixed output of the second of said pair of channels and said multiplier channel is impressed.

25. 13. A system for selectively producing any one of a great number of high frequency carriers, comprising a frequency stabilized master oscillator, a first frequency selector channel for producing coarse frequency increments of the same frequency stability as said oscillator, a second frequency selector channel for producing fine frequency increments of the same frequency stability as said master oscillator, a third channel for producing a fixed frequency which is a multiple of the master oscillator frequency and having the same frequency stability, a coarse frequency subdivider connected between the master oscillator and said first channel, a fine frequency subdivider connected between the master oscillator and the said second channel, the first channel having at least two frequency conversion stages both of which are supplied with selectable local beating oscillations of the same frequency from a local free-running oscillator, the second channel also having at least two frequency conversion stages both of which are supplied with selectable local beating oscillations of the same frequency from a local free-running oscillator, and a frequency mixer electron tube arrangement connected to the said three channels and controlled by their 30 output to produce by frequency conversion any desired high frequency which has the same frequency stability as said master oscillator.

35. 14. A system according to claim 20 in which means are provided to select from the output of the first frequency conversion stage of the first channel the difference frequency for application to the input of the second conversion stage of said first channel, means are provided for selecting from the output of the said second frequency conversion stage of the first channel the sum fre-

11

quency which sum frequency is equal to the input frequency to the first conversion stage of said channel; and the said second channel has means for selecting from the output of the first frequency conversion stage thereof the difference frequency for application to the input of the second frequency conversion stage of said second channel, and means are provided for selecting from the output of the second frequency conversion stage of said second channel the sum frequency which is equal to the input frequency to the first frequency conversion stage of said second channel.

15. A system for selectively producing any one of a great number of high frequency carriers, comprising a crystal-controlled master oscillator, a first frequency selector channel for producing coarse frequency increments of the same frequency stability as said oscillator, a second frequency selector channel for producing fine frequency increments of the same frequency stability of said oscillator, a frequency multiplier channel, all of said channels being controlled by said master oscillator, each of said frequency selector channels having two frequency conversion stages which two stages are excited by the

10
5

12

same local oscillator frequency so that the input frequency to the first stage equals the output frequency of the second stage and is free from ambient changes in the frequency of the local oscillator, an electron tube mixer connected to said three channels and controlled by their respective outputs to produce in the output of said mixer by frequency conversion the said desired high frequency carrier.
